his Atty.

UNITED STATES PATENT OFFICE.

SAMUEL GAGE, OF HOLLOWAY, LONDON, ENGLAND, ASSIGNOR TO THE LONDON GENERAL OMNIBUS COMPANY, LIMITED, OF BROADWAY, WESTMINSTER, LONDON, ENGLAND.

CHAIR OR THE LIKE.

1,390,525.

Specification of Letters Patent. Patented Sept. 13, 1921.

Application filed December 27, 1920. Serial No. 433,094.

To all whom it may concern:

Be it known that I, SAMUEL GAGE, subject of the King of England, residing at Holloway, London, England, have invented certain new and useful Improvements in Chairs or the like, of which the following is a specification.

This invention is for improvements in or relating to chairs or the like and has for one 10 of its objects to provide a convenient means for strengthening the same without detracting from their appearance.

The invention relates to chairs or the like, used for example on omnibuses, of the 15 type having a back whereof a wooden side frame member supports the rear of the seat and forms a leg extending down to the floor, and a specific object of the present invention is to strengthen the said side frame-member 20 in a chair of this type.

It is, of course, well known to employ metal plates for stiffening purposes in furniture and other wooden constructions, and it is not broadly novel to house such stiffening members in slots cut in the wood. It has also been proposed to employ a metal plate to assist in supporting the end of a step in a 25 step ladder, the plate being housed partly in a slot in the side member of the ladder and partly in a slot in the end of the step. This plate was not such as to stiffen the side member, however, its function being, as already indicated, that of assisting in supporting the step. A circular disk-like wooden brace has 30 furthermore been proposed to be inserted in vertical slots cut at the rear end of the under surface of a chair seat, and in the adjacent lower front surface of the rear chair leg. This brace, however, in no way stiffens the chair leg, its function being entirely 35 that of bracing the joint between the chair seat and the chair leg.

The invention may be applied to chairs in which the front and back legs cross each 45 other and also to chairs in which the legs extend downward more or less vertically and are joined by diagonal or other struts. The invention is also applicable to other types of chairs. The weakest part of a chair 50 is at and near the point of attachment of the seat to the back and according to the present invention the wooden side frame members are strengthened at this place.

For a more complete understanding of the

invention there will now be described, by 55 way of example only, and with reference to the accompanying drawings, certain constructional forms of chair according to the present invention. It is to be understood, however, that the invention is not limited to 60 the precise constructional details set forth.

In these drawings:-

Figure 1 is an end elevation of one constructional form of chair, parts being broken away for clearness;

Fig. 2 is a rear elevation of a portion of the chair illustrated in Fig. 1;

Fig. 3 is a section on the line 3—3 of Fig. 1, but on a scale larger than that of this latter figure;

Fig. 4 is an end elevation corresponding to Fig. 1, but of a different type of chair, and

Fig. 5 is a front elevation of certain of the parts shown in Fig. 4. In Fig. 5 certain of the parts are shown in section on the line 75 5—5 of Fig. 4.

Like reference numerals indicate like parts throughout the drawings.

Referring first of all to Figs. 1—3, the construction of chair or the like therein shown 80 is particularly suitable for use upon the roof or upper deck of an omnibus. It comprises a back 10 having a wooden side frame-member 11 which supports the rear of a seat 12 by means of a bolt or the like 13. The 85 frame-member 11 extends down to the floor to constitute a chair leg 14, and this leg 14 crosses another leg 15 which at its upper end supports the front of the seat 12, being secured thereto by a bolt or the like 16. The 90 legs 14 and 15 are also preferably secured together by a bolt or the like 17. There may be members 11, 14 and 15 at each end of the chair, or, as illustrated in Fig. 2, these members may only be situated toward one 95 end of a chair while the other end is supported by some rigid fixture 18 such as, in the construction illustrated, the side framework of the upper deck of an omnibus. As 100 already stated, the weakest part of such a chair is at or near the point of attachment of the seat 12 to the member 11, 14. This member, therefore, is strengthened at this place by being slotted in a front and rear direction intermediate its side faces and throughout 105 a considerable portion of its length above and below the bolt 13. A metal plate 19 is provided which occupies this slot and is

secured to the member 11, 14 by rivets 20 or other suitable means. The reinforcing or flitch plate 19 receives the bolts 13 and 17 and is hidden in the said slot except for a portion 21 which extends forward to pass along the side of a bar 22 secured to the underpart of the seat 12. In the construction illustrated the extension 21 is off-set, see particularly Fig. 3, in order to enable it to lie snugly against the bar 22, and it is secured to the latter by one or more bolts, screws, rivets or the like 23. By this means the seat 12 may be very firmly attached to the back of the chair, and the members composing or supporting the back greatly strengthened, without detracting from the appearance of the chair.

In the construction shown in Figs. 4 and 5, the chair legs 14 and 15 do not cross but are connected by a strut 24. The member 11, 14 is fitted with a metal strip 19 shaped to suit the shape of the member 11, 14 and having an extension 21 for attachment to a bar 22 underneath the seat 12, all in a very similar manner to that above described in connection with Figs. 1-3. The type of chair shown in Figs. 4 and 5 is particularly adapted for use inside an omnibus and can, of course, be upholstered if desired.

30 The invention is particularly applicable to the well-known types of seat used on omnibuses and each of which is intended to receive two passengers, but it is also applicable to other types of chair.

35 By the employment of the reinforcing plates according to the present invention the neatness and lightness of a wooden chair is retained with the addition of considerable strength at the point where it is most needed.

40 What I claim as my invention and desire to secure by Letters Patent is:—

1. In a chair or the like the combination with a seat of a back comprising a wooden side frame-member which supports the rear of the seat and forms a leg extending down to the floor, said frame-member being slotted in a front and rear direction, intermediate its side faces, and throughout a considerable portion of its length adjacent the point of attachment to the seat, a metal flitch plate 19 which occupies said slot and has an off-set forward extension 21 reaching adjacent to a side face of said bar, means for securing said flitch plate to the frame-member to stiffen and strengthen the latter.

2. In a chair or the like the combination with a seat of a back comprising a wooden side frame-member which supports the rear

of the seat and forms a leg extending down to the floor, said frame-member being slotted in a front and rear direction, intermediate its side faces, and throughout a considerable portion of its length adjacent the point of attachment to the seat, a metal plate which occupies said slot and has a forward extension, means for securing said plate to the frame-member to stiffen and strengthen the latter, and means for securing said forward extension to the seat.

3. In a chair or the like the combination with a seat 12 having underneath it a bar 22 extending in the front and rear direction, of a back comprising a wooden side frame-member 11 which supports the rear of the seat and forms a leg 14 extending down to the floor, said frame-member being slotted in a front and rear direction, intermediate its side faces, and throughout a considerable portion of its length adjacent the point of attachment to the seat, a metal flitch plate 19 which occupies said slot and has an off-set forward extension 21 reaching adjacent to a side face of said bar, means for securing said flitch plate to the frame-member to stiffen and strengthen the latter, and means for securing said forward extension to the said bar.

4. In a chair or the like the combination with a seat 12 having underneath it a bar 22 extending in the front and rear direction, of a back comprising a wooden side frame-member 11 which supports the rear of the seat and forms a leg 14 extending down to the floor in a forward direction, another leg 15 which supports the front of the seat and which extends down to the floor in a rearward direction, said legs crossing each other, said frame-member being slotted in a front and rear direction, intermediate its side faces and throughout a considerable portion of its length including the point of attachment to the seat and the point at which it crosses the other leg, a metal flitch plate 19 which occupies said slot and has an off-set forward extension 21 reaching adjacent to a side face of said bar, means for securing said flitch plate to the frame-member, means for securing said forward extension to the said bar and a bolt for securing said legs together at the point at which they cross, said bolt passing through the flitch plate.

In testimony whereof I affix my signature.

SAMUEL GAGE.
